UNITED STATES PATENT OFFICE.

ELI MAYNARD LONG, OF GENEVA, NEW YORK, ASSIGNOR TO SHUR-ON STANDARD OPTICAL COMPANY, OF GENEVA, NEW YORK, A CORPORATION OF NEW YORK.

LENS GRINDING AND POLISHING MACHINE.

Application filed December 10, 1926. Serial No. 153,880.

This invention relates to a lens grinding and polishing machine in which the movable elements of a plurality of, in this instance two, grinding and polishing couples are synchronously reciprocated in different directions preferably at right angles to each other and, therefore, along serpentine paths to impart the desired contour and finish to the surface of the lens or other object operated upon and involves the use of a third motion by which the paths of travel of the movable elements are changed during successive strokes and cycles of movement and thereby to prevent the formation of stria or other deformations incidental to the travel of the movable elements along one and the same path.

The main object is to provide simple and efficient means for effecting a slow but continuous (not intermittent) movement of the movable elements from the normal path of travel resulting from the compound reciprocal movements in different directions and thereby to avoid the jar and incidental irregularity of abrasion of the lens due to any abrupt or intermittent shifting of the normal paths of movement of the movable elements thus permitting the lens to be more expeditiously and accurately ground or polished to the desired contour and finish than has heretofore been practicable.

Another object is to provide means whereby the amplitude of the transverse movement of the movable elements may be easily and quickly varied by a simple adjustment without removing any of the parts of the machine.

Other objects and uses relating to specific parts of the machine will be brought out in the following description.

In the drawings:

Figure 1 is a perspective view of a lens-grinding, polishing and surfacing machine embodying the various features of this invention.

Figure 2 is an enlarged top plan, partly in section, of the same machine with the top removed to show the interior parts.

Figure 3 is a transverse vertical sectional view taken in the plane of line A—A, Figure 2.

Figures 4 and 5 are transverse vertical sectional views taken in the planes of lines B—B and C—C, respectively, Fig. 2.

Figure 6 is an enlarged detail sectional view taken in the plane of line D—D, Figure 5.

Figure 7 is an enlarged detail sectional view taken in the plane of line E—E, Figure 2.

Figure 8 is an enlarged longitudinal vertical sectional view of the same machine taken in the plane of line F—F, Fig. 1.

Figure 9 is an enlarged detail sectional view taken on line G—G, Figure 2.

Figure 10 is an enlarged detail sectional view taken on line H—H, Figure 2.

Figure 11 is a detail sectional view taken in the plane of line I—I, Figure 10.

As illustrated, this machine comprises a main supporting frame consisting of a box section or housing —1— and a top section —2— which is secured by screws or bolts —3— to the box section —1— and is provided with a lid —4— hinged thereto to permit access to the interior mechanisms when opened and to exclude dust and other foreign matter when closed, the box section —1— being provided along the lower edge of its front side with a work and tool-supporting shelf —5—.

A main driving shaft —6— is journaled in suitable bearings —7— and —7'— of one of the end walls and rear side wall of the housing —1— to revolve about a horizontal axis and is provided with external tight and loose pulleys —8— and —9— and a hand wheel —10— by which it may be turned independently of the tight pulley —8— which may be driven from any available source of power by a suitable belt capable of being shifted from the tight to the loose pulley and vice versa by means of a shifting rod —11— and hand lever —12— as shown more clearly in Figure 2, said shifting rod and lever being mounted upon suitable brackets —11'— and —12'— on the rear side and at one end of the case respectively.

The machine is adapted to operate the movable elements of a plurality of, in this instance two, lens surface grinding and polishing couples, each comprising a relatively stationary lap-supporting element —13— and a movable lens-carrying element —14—, the lap-supporting element —13— being adapted to receive and support a grinding lap —15— shown by full lines in Figures 1 and 2 and by dotted lines in Figure 4 while

the lens-carrying element —14— is operatively connected to a lens-supporting block —16— for moving the lens as —a— across and upon the upper surface of the lap —15— which may be provided with an abrasive paste for effecting the desired grinding and polishing of the lens to conform to the upper surface of the lap.

These laps are, of course, of various contours and must be interchanged from time to time upon the supporting elements —13— and are releasably held in operative position thereon by a cam shaft —17— and opposite diagonal pins —18— adapted to enter corresponding sockets in the underside of their respective laps.

Each cam shaft —17— is journaled in its corresponding element —13— to rotate about a vertical axis and is provided with a handle —19— by which it may be turned to its lap-releasing position against the action of a retracting spring —20— which serves to hold the cam shaft in its lap-locking position with the handle —19— engaging a limiting stop —21— as shown in Figure 10.

The lap-supporting members —13— are mounted upon separate brackets —22— which in turn are adjustably secured by a bolt —23— to the front face of the front wall of the case —1— so as to be capable of lengthwise adjustment thereon, said brackets being provided with forwardly projecting studs —24— upon which the members —13— are directly mounted for forward and rearward adjustment and are held in their adjusted position by set screws —25—, Figure 10.

Each of the members —13— is also provided with a threaded socket —26— for receiving stop screws —27—, the rear ends of which are slidable in apertures —28— in their respective brackets —22— and are adapted to engage the front face of the case —1— for limiting the rearward movement of the lap-supporting member —13— and also serving to hold said members against turning movement upon their supporting studs —24—.

The lens carrying elements —14— are pivotally mounted for tilting movement upon suitable supports within the case —1— and extend outwardly through openings —29— in the front wall of the case —1— so as to overlie and project forwardly beyond the corresponding lap-supporting elements —13— and are provided with pins —30— for engaging in sockets in the upper sides of the adjacent lens-supporting members —16— for moving the lens across the surface of the lap as the members —14— are reciprocated in a manner hereinafter described.

A pair of upright standards or guides —31— are secured by bolts —32— to the top section —2— near the front edge thereof to extend upwardly therefrom for receiving and supporting a pair of vertically movable arms —33—.

A pair of levers —34— are pivoted at —35— to their respective arms —33— and are connected by links —36— to the upper ends of the guides or standards —31— as shown in Figure 4 whereby the forward and rearward rocking movement of the hand levers —34— will effect a corresponding vertical movement of the arms —35— which are preferably arranged directly over and some distance above their respective lens supporting arms —14—.

A pair of leather adjusting straps —37— are secured at their lower ends to the front ends of their corresponding lens-supporting arms —14— and are adjustable vertically through openings —38— in the arms —33— for effecting a corresponding vertical adjustment of the arms —14—, said straps being held in their adjusted positions by set screws —39—, Figure 1 to limit movement of the lens-holder toward the lap —15— and to allow the lens-holder to yield vertically.

The object of the adjustments of the lap-supporting block —13— is to bring the lap within the range of movement of the lens-holder —16— while the object in adjusting the lens-carrier —14— vertically by means of the strap —37— is to position the lens-holder —16— in proper grinding and polishing relation to the lap and also to permit the removal and replacement of the lens-holder —16— with the lens thereon.

The lower end of the lens-carrier —14— is yieldingly held in its pressing position by means of an upright pressure rod —40— and a spring —41— which is interposed between a shoulder —42— on said rod and the underside of the front end of the arm —33—, said rod having its lower end engaged with the front end of the arm —14— and its upper end guided in an aperture —43— in the arm —33— as shown in Figure 4.

Lengthwise reciprocal movement.

Suitable mechanism is provided for transmitting compound and synchronous reciprocal motion from the main driving shaft —6— to the movable grinding element, in this instance, the lens-carrier —14— and for this purpose the driving shaft —6— is provided with a worm gear —44— and an eccentric extension stud —45—, the worm gear —44— being secured to the intermediate portion of the shaft within the housing —1— and adjacent the inner end of the bearing —7— while the eccentric stud —45— forms a continuation of the inner end of said shaft within said housing to rotate bodily about the axis thereof.

The worm gear or pinion —44— meshes with the upper side of an underlying relatively larger gear —46— which is journaled upon a relatively stationary shaft or stud —47— to rotate about an axis at right angles to the axis of the driving shaft —6—, said station-

ary shaft or stud being removably secured by a set screw —48— to the rear wall of the case —1—, Figure 3, to extend forwardly therefrom.

5 A yoke member —49— is journaled on the inner end of the stationary shaft —47— and is operatively connected by arms —50— to the gear —46— to rotate therewith and to form an intervening space for receiving a 10 pair of collars —51— which are secured to the stationary shaft —47— by set screws —52— to hold the gear —46— and yoke member —49— against axial movement.

15 A stub shaft —53— (Figure 9) is journaled for angular adjustment in the yoke member —49— at one side of and parallel with the stationary shaft —47— and is held in different positions of angular adjustment by means of a clamping screw —54— and a 20 friction block —55—, said screw being engaged in a diametrically extending threaded aperture in the stud —53— while the friction block —55— is seated in one or the other of a pair of diametrically opposite recesses in 25 the stud —53— and is adapted to frictionally engage the adjacent wall of the opening in which the stud —53— is journaled when the screw —54— is tightened.

30 The screw —54— extends through a circumferentially elongated slot —56— in the yoke member —49— to permit relative rotary adjustment of the stud —53— for a purpose presently described.

35 The stub shaft —53— is provided with a disk —57— carrying an axially-extending stud —58— which is eccentric to and parallel with the stub shaft —53—.

40 This eccentric pin —58— serves as the initial driving means for reciprocating the lens supporting arms —14— of both of the lens-holders —14— lengthwise of the axis of the main driving shaft —6— and for this purpose is provided with a sleeve —59— journaled thereon, said sleeve being pivotally connected to one end of a link —60— having its other end connected by a universal joint —61—, Figure 5, to a floating frame —62—.

45 This frame —62— is free to move longitudinally and transversely of the main driving shaft —6— and is pivotally supported in a substantially horizontal plane upon a pair of longitudinally spaced upright supports —63—, Figures 4 and 8, which, in turn, are pivotally mounted upon a vertically oscillating frame —64— for rocking movement about parallel axes at right angles to the axis of the driving shaft —6— for reciprocating the movable elements of the lens grinding and polishing couples lengthwise of the axis 55 of the driving shaft.

60 The upper ends of the upright members —63— are bifurcated to receive adjacent portions of opposite ends of the floating member —62— to which they are pivoted at —65— so 65 that the floating member —62— constitutes

a connecting link between the upper ends of its supporting arms —63— for simultaneously rocking said arms in reverse directions as the floating member —62— is reciprocated lengthwise of the shaft —6— by the rotation 70 of the yoke member —49— through the medium of the eccentric pin —58— and link —59—.

75 A pair of reversely arranged substantially L-shaped arms —66— and —67—, Figures 2 and 8, are pivotally mounted at —68— and —69— respectively upon the floating member —62— to swing about co-axial axes parallel with the axis of the driving shaft —6— and in substantially the same horizontal plane as the pivotal connection —65— between the floating member —62— and its supporting arms —63—, the L-shaped members —66— and —67— being movable vertically independently of each other for a purpose presently described.

80 The lens-carrying elements —14— are pivoted at —70— to the L-shaped arms —66— and —67— respectively to swing about parallel axes at substantially right angles to the driving shaft —6— to compensate for varying positions of their respective lens-holders —16— when moving across the faces of their corresponding laps, the pivots —70— of each lens-operating arm —14— being disposed in 85 approximately the horizontal plane of and nearly co-axial with the pivots —65—.

Transverse movement.

90 The frame —64— is pivotally mounted at —71— upon suitable lugs on the bottom of the case —1—, Figure 8, to rock vertically about a horizontal axis parallel with the axis of the driving shaft —6— and to which the upright members are pivoted at —63'— at the 95 front and rear sides of the pivots —71— for the frame —64—, see Figures 4 and 8.

100 A curved arm —72— is adjustably secured at one end by a set screw —73— to the central portion of the frame —64— to extend rearwardly therefrom some distance below and substantially concentric with the axis of the main driving shaft —5—.

105 A yoke member —74— is adjustable lengthwise of and upon the curved portion 110 of the arm —72— and is held in its adjusted position by a set screw —75—, Figures 5 and 6, and is provided with a cylindrical bearing —76— in which is journaled a rotary eccentric —77—.

115 The eccentric —77— is journaled upon a stud —78— which, in turn, is secured to the lower end of a connecting rod or pitman —79— having its upper end provided with a journal bearing —80— for receiving the eccentric extension —45— of the driving shaft —6—, as shown in Figures 2 and 6, whereby as the shaft —6— is rotated the pitmen —79— will be reciprocated endwise by the eccentric —45— for imparting oscillatory 120 125 130

motion to the frame —64— through the medium of the arm —72— and effecting a corresponding backward and forward or transverse movement of both of the movable elements —14— of the grinding and polishing couples through the medium of the upright arms —63—, floating member —62— and L-shaped arms —66— and —67—.

10 *Third movement.*

An upwardly inclined shaft —81— is journaled in suitable bearings upon the pitman —79— and is provided at its upper end with a gear —82— meshing with a companion gear worm —83— on the inner end of the eccentric extension —45— to which it is secured, the lower end of said shaft being provided with a worm —84— meshing with a worm gear —85— on the inner end of the eccentric sleeve —77—, Figures 5 and 6, whereby as the pitman —79— is reciprocated for moving both of the lens-carrying elements —14— transversely of the driving shaft the rotation of the eccentric —77— will cause a gradual but continuous shifting of the arc of movement of the frame —64— which, in turn, will cause a corresponding shifting of the stroke of the transverse movement of the lens-carrying arm —14— and lens-holders —16— actuated thereby relatively to their respective lap-supporting members —13—.

It will be seen from the foregoing description that these three movements, viz., (1) the lengthwise movement, (2), the transverse movement, and (3) the shifting movement of the lens-carrying elements —14— and lens-holder —16— actuated thereby, will be synchronous and simultaneous resulting in the travel of the lens-holder across the face of the lap in serpentine paths and also in the gradual but continuous changing of these paths during successive lengthwise and transverse strokes of the lens-carriers.

45 *Lubricating means.*

The gear wheel —46— is provided with a cam groove —86— for receiving a roller —87— which is mounted upon the intermediate portion of a rock arm —88—, Figure 7, having one end pivoted at —89— to a bracket —90— on the main supporting frame —1— near the rear wall thereof.

The other end of the lever —88— is connected by a pitman —91— to the lower end of an outer upright tube —92— which, in turn, is slidably lengthwise of and upon an inner upright tube —93— having its upper end threaded and secured in a threaded socket —94— in the bracket —90— as shown more clearly in Figure 7.

60 The inner chamber of the case —1— contains a quantity of oil for lubricating purposes into which the lower ends of the tubes —92— and —93— normally extend, said tubes being provided near their lower ends with oil

inlet ports —95— and —96— respectively controlled by check valves —97— and —98—.

These tubes constitute what may be termed a piston pump, the outer tube being reciprocated vertically upon the inner tube by the 70 rotation of the gear wheel —46— and its cam groove —86— which, in turn, oscillates the lever —88— for reciprocating the outer tube —92—.

When the pump tube —92— is lowered the 75 oil enters the ports —95— and —96— thereby opening the valves —97— and —98— as long as the outer tube continues its descent thereby causing a quantity of oil to be forced into the interior of the inner tube —96— so that when 80 the outer tube is raised the valve —97— will automatically close trap the oil in the inner tube and force it upwardly into the chamber —94— and thence through suitable distributing pipes —99— leading from the chamber —94— to such bearings as may require lubrication, the upper sides of the inner ends of the lens-carrying arms —14— being provided with V-shaped grooves —10— for receiving lubricant from the distributing pipes 85 —99— and thereby lubricating the bearings —65— and —70—.

The purpose of the rotary adjustment of the rotary stub shaft —53— carrying the eccentric pin —58— is to bring said pin 95 nearer to or farther from the axis of the shaft —48— for varying the lengthwise stroke of the link —60— and floating member —62— actuated thereby and to cause a corresponding variation in the longitudinal movement of 100 the lens-carrying members —14—.

To effect this rotary adjustment the clamping screw —54— will be loosened and moved along the slot —56—, Figure 9, thereby effecting a corresponding bodily movement of the pin —58— about the axis of the stub shaft —53— toward or away from the axis of the shaft —47— as shown by dotted lines in Figure 9.

If it is desired to increase the amount of 110 throw of the eccentric pin —58— the clamping screw —54— may be removed from the stop shaft —53— and the latter turned half way around to effect a corresponding bodily movement of the eccentric pin —58— whereupon the clamping screw —54— may be re-inserted in the threaded opening in the stub shaft —53— and tightened when the proper adjustment is effected to hold the eccentric pin —58— in fixed relation to the stub shaft 115 —53— and yoke member —49—.

120 *Operation.*

When the lens-holders with the lenses thereon are placed in operative position for grinding or polishing and the driving shaft —6— is being rotated, rotary motion will be transmitted from the pinion —44— to the gear —46— and yoke member —49— connected thereto thereby moving the eccentric stub 130

shaft —53— bodily about the axis of the shaft —47— and causing similar bodily movement of the eccentric pin —58— about the axis of the shaft —47—.

5 This bodily movement of the eccentric pin —58— about the axis of the shaft —47— and sleeve —59— which is mounted upon said pin causes a corresponding reciprocal movement of the link —60— and floating member —62— lengthwise of the axis of the driving shaft and also rocks the supports —63— in the same directions.

10 This lengthwise movement of the floating member —63— is transmitted to the L-shaped arms —66— and —67— and thence through said arms to the lens-carrier —14— which are pivotally mounted upon their respective arms —67— and cause corresponding movements of the lens-holders —16— upon their 15 respective laps —15— in the direction of length of the axis of the driving shaft —6—.

15 Simultaneously with these movements the eccentric extension —45— on the inner end of the main driving shaft —6— is rotated 20 bodily about the axis of said driving shaft and through the medium of the pitman —79— transmits vertical reciprocatory motion to the stud —78— and thence through the eccentric —77— and yoke —78— to the 25 curved arm —72— for rocking the frame —64— vertically about the axis of its pivots —71— and therefore transversely of the axis of the main driving shaft —6—.

30 This transverse rocking movement of the member —64— is transmitted to the upright arms —63— and thence to the floating member —62— carrying the arms —66— and —67— from which transverse movement is imparted to the lens-carriers —14—.

35 During these lengthwise and transverse movements of the lens-holders —14— the shaft —81— is slowly rotated to effect a still slower rotation of the eccentric —77— which, in turn, gradually shifts the arm 40 —72— of the frame —64— vertically thereby causing a variation in the transverse path 45 of movement of the lens-holders and effecting a corresponding change in the serpentine paths of movements of both of the lens on 50 their respective laps during successive cycles of operation lengthwise and also transversely of the main driving shaft for preventing the formation of stria or deformations of the lens surfaces.

55 What I claim is:

1. In a lens-grinding and polishing machine having an abrasive element and a lens-holding element, a rotary driving shaft hav-

ing an eccentric, a pitman journaled on the eccentric, a driven shaft journaled on the pitman and provided with an eccentric, means for transmitting rotary motion from the driving shaft to the driven shaft, a yoke journaled on the eccentric of the driven shaft, a pivotally supported frame operatively connected to and oscillated by the yoke, a floating frame operatively mounted on the first-named frame to move therewith in reverse directions and having an independent reciprocal movement in a different direction, 60 means actuated by the driving shaft for effecting said independent movement, and means for transmitting motion from said floating frame to one of said elements.

2. In a lens-grinding and polishing machine, a lens-grinding element, a lens-holding element, movable supporting means for one of said elements, a rotary driving shaft, means actuated by said shaft for reciprocating said supporting means transversely of the shaft, and means actuated by said shaft for reciprocating said supporting means lengthwise of the shaft, the second-named means including means for automatically varying the amount of movement of the supporting means transversely of and during each revolution of the shaft.

3. In a lens-grinding and polishing machine, a lens grinding element, a lens-holding element, movable supporting means for one of said elements, a rotary driving shaft, means actuated by said shaft for reciprocating said supporting means lengthwise of the shaft and including means adjustable at will for varying the amount of movement of said supporting means, and means actuated by said shaft for reciprocating the supporting means transversely of the shaft.

4. In a lens-grinding and polishing machine, a lens-grinding element, a lens-holding element, movable supporting means for one of said elements, a rotary driving shaft, a rotary driven member actuated by said shaft, a crank pin mounted on said driven member and adjustable at will to different distances from the axis of the driven member, means for holding the crank pin in its adjusted position, means actuated by the crank pin for reciprocating said supporting means, and means actuated by the driving shaft for reciprocating the supporting means in a different direction from that produced by the crank-pin.

In witness whereof I have hereunto set my hand this 26 day of November 1926.

ELI MAYNARD LONG.
